UNITED STATES PATENT OFFICE.

JOHN P. WEIS, OF NYACK, NEW YORK, ASSIGNOR TO ECONOMY BAG CLOSING COMPANY,
OF KNOXVILLE, TENNESSEE.

SEWING-MACHINE.

1,258,965.

Specification of Letters Patent. Patented Mar. 12, 1918.

Application filed September 11, 1914. Serial No. 861,196.

To all whom it may concern:

Be it known that I, JOHN P. WEIS, a citizen of the United States, residing at Nyack, in the county of Rockland and State of New York, have invented certain new and useful Improvements in Sewing-Machines, of which the following is a specification.

This invention relates to that class of sewing machines particularly adapted for sewing filled bags, the sewing mechanism being so mounted that the main driving shaft is in a vertical position while the needle bar operates horizontally so that the stitching position of the bag is at the end of the machine with no projecting parts of the machine extending below the stitch line to interfere with the filled bags as they are passed to and from the sewing machine by means of a conveyer commonly used for this purpose.

In the present improvement the entire working mechanism for operating the needle, looper and feeding device is so arranged as to provide a clear space underneath the machine for the positioning of the work so that a bag may be filled to its full capacity leaving just a short margin at the top of the bag so that such top portion may be drawn together and stitched while it is fed to and from the machine by mechanical means.

The object of the invention therefore is the provision of an improved sewing machine of the class referred to, comparatively simple and reliable in its operation and by means of which the work to be done can be more readily and quickly accomplished.

A further object of the invention is the provision of an improved feed device operating mechanism.

In the drawings accompanying and forming part of this specification, Figure 1 is an end view of the machine; Fig. 2 is a bottom view of the machine shown in Fig. 1; Fig. 3 is a side view of the machine shown in Fig. 2 with the arm broken away on the line 2-2; Fig. 4 is a sectional view of the bottom plate, taken on the line 1-1, Fig. 2, and looking in the direction of the arrow; Fig. 5 is a detail perspective view of the feed mechanism; Fig. 6 is a detail of the throat plate; and Fig. 7 is a view partly

in section of the actuating means for the feed bar.

Similar characters of reference indicate corresponding parts throughout the several figures of the drawings.

The main supporting plate 1 of the machine carries suitable bearings 3 and 4 for the vertically supported main driving shaft 2. Carried by the plate 1 is a laterally extending overhanging arm 5, the outer part 6 thereof carrying at its lower end the needle bar 8 carried by bearings 7, the presser foot bar 9, and the guide bar 10, all of which are supported by suitable bearings. The guide bar 10 and presser foot bar 9 are connected by a cross-member 12 clamped thereto, and this guide bar 10 reciprocates in its bearings 11. A spring 13 rests thereon to give pressure to these bars and a screw 14 serves to regulate the tension thereof.

A presser foot lifting collar 15 is also clamped to the bar 9 to co-act with the hand lifter 16 which is pivoted at 17 to the machine frame. A presser foot 19 is pivoted at 20 to its shank 18 which is secured to the bar 9. This foot has a portion 21 and an out-turned extending end 22. The main shaft 2 carries a belt wheel 23 and an eccentric 23' which operates a connection 24, the opposite end 25 of which is formed to embrace a ball stud carried by the needle lever 26 which lever is pivoted at 27 to the arm 5, and actuates the link 28 pivotally secured thereto at 29, and the other end of which link is pivoted at 30 to the needle bar clamp collar 31 for the purpose of reciprocating the needle 32 which is suitably clamped in its bar. This needle lever 26 has an extending end 34, having pivotally connected thereto at 35 a looper actuated rod 36, the other end of which is pivoted at 37 to the looper driver 38 to rock or reciprocate the looper 39 into and out of the needle loop, and this looper is pivoted at 40 for rocking motion so that the looper may move from the front to rear of the needle during the stitch formation. The looper driver is also pivotally secured at 41 to the looper bracket 42 secured to the plate 1 by a screw 43. A shaft 44 is reciprocated in the bracket 42 by means of another eccentric 45 carried by the main shaft 2 at the lower end thereof,

90
95
100

which eccentric operates in a yoke 46 carried by the looper shaft 44. A reduced end of the looper shaft extends into this yoke hub 47 and the end motion of the yoke on the shaft is controlled by the nuts 48.

From the foregoing it will be seen that rotation of the wheel 23 and main shaft 2 reciprocates the connection 24 and thereby the needle lever 26 to reciprocate the needle 10 and looper while at the same time the other eccentric 45 is so timed as to reciprocate the looper shaft 44 so as to move the looper end 49 seated in the shaft 44 and thus rock it on its pivot 40 so as to move the looper 15 from the rear of the needle where it takes the needle loop to the front thereof where it presents the looper loop to the needle, completing the stitch. This mechanism is similar to that described in Weis Patents 20 Nos. 933,407 and 990,414. The needle thread is handled in the usual manner, common to this type of machine. The looper thread is also handled and controlled by a pull-off, takeup and nipping mechanism 50 similar 25 to that shown in the patent to Weis No. 933,408, and therefore a detailed description of this mechanism is unnecessary.

The feeding mechanism is controlled by the hand wheel connection 24 which is provided with an extending lug 51 carrying a ball stud 52, see Fig. 7, clamped therein by a nut 53. The ball of this stud operates in a socket 54 of the feed bar 55, which extends from one end of the machine to the other, 30 and in substantial parallelism with the driving shaft. The ball stud 52 may be provided with a ring 52' to fit in the socket 54 which would give a larger bearing contact and longer life. To properly guide this improved form of feed bar a double forked yoke 57 is provided and the feed bar moves in one forked end 56 thereof. This yoke is pivotally secured to the machine plate 1 by a pivot screw 58 having a nut 59 thereon. This yoke is also provided with a 40 forked end 61 bored to receive a pivot pin 62 for supporting the feed bar 55. This pin is secured in the feed bar by means of a screw 63, see Fig. 5. The feed bar terminates in an extension 64 cut out to receive a feed dog or device 65 which is segmental in shape to conform with the arc that the bar 55 and the yoke 57 swings in by reason of the pivot screw 58. As the 45 wheel 23 and eccentric 23' rotate, a lifting motion is given to the ball stud 52 and the end of the feed bar 55 so that it moves in the forked end 56 and is guided thereby. Simultaneously with this lifting motion, the 50 connection 24 moves laterally swinging the bar 55 and its yoke 57 on its stud 58, and the reversal of these movements thus gives a four motion to the feed dog, and this motion is substantially the same as that 55 given by the usual two eccentrics, where one

is used to reciprocate the feed laterally and the other is used to reciprocate it vertically. In the type of machine shown, it is desirable to have a fixed feed stroke so as to give a positive feeding action on all classes 70 of work to insure a uniform length of stitch. The feeding mechanism must be entirely out of the path of the contents of the bag and the device described has been found very satisfactory for this work because of the 75 long leverage of the feed bar and the circular motion thereof as this tends to lift the loose end A of the filled bag B, see Fig. 1. From the foregoing it will be observed that the feeding mechanism in the present improvement is so connected as to obtain all of its feeding movements from the needle driving means at the upper end of the machine. In other words, the hand wheel connection or eccentric which reciprocates the 80 needle lever and the needle bar and also the looper bar also operates the feed bar in such manner as to give the feed dog a circular feeding movement and also a rise and fall movement, so that when the bags to 85 be stitched are led into the machine the feeding motion is such that it tends to lift the loose or free edges of the bag vertically so as to stitch same across the top in a uniform manner. And so far as I am aware, I am 90 the first to provide a bag machine in which the feed operating bar is so located and connected that its operation will tend to lift the free or loose edge of the bag to be sewed in a vertical direction. 100

In order to handle the filled bags with ease and rapidity it is essential to have the end of the machine carrying the stitching mechanism of peculiar shape to form a bag neck receiving opening or mouth portion, 105 and therefore I have provided the presser foot with a turned out part as 22 practically conforming to the inclined front edge 68 of a bottom plate 69, see Fig. 2. This plate 69 is arranged to support the throat 110 plate 67 which is secured thereto by screws 70, and cut out as at 71 and 72, see Fig. 2, to prevent the dirt from interfering with the operating mechanism as on this class of work the filling material used in the bags 115 is apt to deposit in the machine and cause undue wear of the mechanism. The cut out portion 71 also permits the looper 39 to operate therethrough. As the machine operates rapidly every facility must be provided 120 so that the bags can be fed into the sewing machine with ease. It is for this reason that an extended presser foot and a peculiar shaped bottom plate is provided so as to present a free opening at C, see Fig. 2, to 125 readily take the bag with little guidance and hold it in the position shown by dotted lines at A, Fig. 1, while it is stitched across the top. Simultaneously with this operation a stock tag is often stitched in with the 130

bag, and this must be presented to the machine by the attendant as the bag is being stitched. A needle guard 73 is located at one side of the needle and is secured to the bottom plate 69 as at 74, and it has a suitable adjustment to suit the various sizes of needles used. At the rear of the bottom plate 69 is secured a cutting blade 75, see Figs. 2 and 3, which cooperates with a 5 swinging blade 76 pivoted at 77 to a hub 78 and actuated by a link 79 pivotally connected at 80 to the blade and at 82 to an actuating lever 81. This lever 81 is pivoted to the machine support at 84 and extends 10 as at 85 outward and carries a pad 86 in position to be actuated by the hand of the operator for the purpose of bringing the knives to a position to sever the chain of stitching after each bag is sewed. Sur- 15 rounding the pivot 84 is a coil spring 89, see Fig. 1, having one end entering a hub 90 and the other end entering an adjustable collar 91 held in position by a nut 93.

This machine is intended for use in connection with the apparatus described in Patents Nos. 924,175, 918,184, 973,123, and 1,009,165, to J. E. Miller, wherein a conveyer is used to bring the bags of various sizes up to the sewing machine for the purpose of closing the mouths by sewing, in which the apparatus is designed to handle bags of varying sizes, at times alternating with one another, and comprises means of adjusting the conveyer instantly for the 20 various sizes of bags to present them to the sewing machine for the proper stitching. The operation of the conveying mechanism of the sewing machine, the presentation of the bag mouths to the stitching mechanism, 25 the starting and stopping of the sewing machine, and the cutting of the threads after the bags have been sewn, may all be taken care of by one attendant.

In order to cover the entire working 30 mechanism and protect the operator from the same, I have provided a swing cover plate 100, shown in section in Fig. 1 and in an open position in Fig. 3. A portion of this plate 101 overhangs the takeup mechanism, and a portion 102 covers the main shaft and a part of the feed and looper mechanism. A pin 103 cooperates with a swinging latch 104 to hold the cover plate when in a closed position. The cover plate is hinged 35 in position as at 105 and can be swung out of position as shown in Fig. 3 to give free access to the moving parts for the purpose of threading, etc.

From the foregoing it will be observed 40 that the looper and feeding mechanisms are all located in a comparatively small space and within the casing formed by the main supporting or side plate, the bottom plate and the hinged cover, whereby they are pro- 45 tected from dirt and contents of the filled

bags, and that the feed bar extends from one end, as the lower end of the machine, to the opposite, or upper, end of the machine, at which latter point it is connected with the driving shaft by means of which 70 it is operated, so that the driving means for this feed bar is entirely away from the stitching mechanism.

It will be understood that the various details may be more or less modified without 75 departing from the spirit or scope of the present improvement.

I claim as my invention:

1. In a sewing machine of the class described, the combination of supporting 80 means, an upright main driving shaft, stitching mechanism connected therewith, and feeding mechanism including a feed device and an upright feed bar connected at one end with said device and at its opposite 85 end with said main driving shaft, said feed bar being so supported and connected with the driving shaft as to give the feed device a circular feeding movement including a rising motion thereby tending to lift the loose 90 or free edges of the bag vertically so as to stitch the same across the top uniformly.

2. In a sewing machine of the class described, the combination of supporting means, an upright main driving shaft, 95 stitching mechanism connected therewith, and feeding mechanism including a feed device and an upright feed bar connected at one end with said device and at its opposite end with said main driving shaft, said driving shaft and bar extending in substantial 100 parallelism one with the other, and said feed bar being so supported and connected with the driving shaft as to give the feed device a circular feeding movement including a 105 rising motion thereby tending to lift the loose or free edges of the bag vertically so as to stitch the same across the top uniformly.

3. In a sewing machine of the class described, the combination of supporting means, an upright main driving shaft, stitching mechanism connected therewith, feeding mechanism including a feed device and an upright feed bar connected at one 110 end with said device and at its opposite end with said main driving shaft, and a pivotally supported bifurcated yoke for supporting and guiding said feed bar, said feed bar being so connected with the driving 115 shaft as to give the feed device a circular feeding movement including a rising motion thereby tending to lift the loose or free edges of the bag vertically so as to stitch the same across the top uniformly. 120

4. In a sewing machine of the class described, the combination of supporting means, an upright main driving shaft, stitching mechanism connected therewith, feeding mechanism including a feed device 130

and an upright feed bar connected at one end with said device and at its opposite end with said main driving shaft, and an eccentric connecting mechanism between the upper end of said driving shaft and the upper end of said feed bar, the connection of said feed bar being such that the feed device is given a circular feeding movement including a rising motion thereby tending to lift the lower or free edges of the bag vertically so as to stitch the same across the top uniformly.

5. In a sewing machine of the class described, the combination of supporting means, an upright main driving shaft, stitching mechanism connected therewith, feeding mechanism including a feed device and an upright feed bar connected at one end with said device and at its opposite end with said main driving shaft, a pivotally supported bifurcated yoke for supporting and guiding said feed bar, and an eccentric connecting mechanism between the upper end of said driving shaft and the upper end 20 of said feed bar, the connection of said feed bar being such that the feed device is given a circular feeding movement including a rising motion thereby tending to lift the lower or free edges of the bag vertically so as to 25 stitch the same across the top uniformly.

6. In a bag sewing machine having stitching mechanism and feeding mechanism, the stitching mechanism including a needle and driving means therefor, the feeding mechanism being so supported and connected with the needle driving means as to obtain all of its movements therefrom and to give a circular movement including a rising motion to the feed thereby tending to lift the loose or 35 free edges of the bag vertically in the direction of the length of the bag, when the bag is fed to the machine with its free edges projecting upright and in a direction coinciding with the length of such bag so as to 40 stitch the same across the top thereof in a uniform manner.

7. In a bag sewing machine having stitching mechanism and feeding mechanism, the stitching mechanism including a horizontally movable needle bar and needle, a needle lever therefor, an upright driving shaft connected with the needle lever, an upright feed bar also connected with the needle lever connecting means whereby all of its 50 movements are obtained from the needle driving means, the connection of the feed bar with the needle driving means being such that the feed is given a circular movement including a rising motion tending to 55 lift the loose or free edges of the bag vertically so as to stitch the same across the top uniformly.

8. In a bag sewing machine having stitching mechanism and feeding mechanism, the stitching mechanism including a horizon-

tally movable needle bar and needle, a needle lever therefor, an upright driving shaft connected with the needle lever, a looper also connected with the needle lever, an upright feed bar also connected with the needle lever connecting means whereby all of its movements are obtained from the needle driving means, the connection of the feed bar with the needle driving means being such that the feed is given a circular movement including a rising motion tending to lift the loose or free edges of the bag vertically so as to stitch the same across the top uniformly.

9. In a sewing machine, the combination of supporting means, a main driving shaft carried thereby, stitching mechanism connected therewith, feeding mechanism including a feed device and a feed bar extending in substantial parallelism with said main shaft and connected at one end with said device and at its opposite end in proximity to one end of said driving shaft, and means for supporting and guiding said feed bar between its ends and comprising a 85 forked pivotally supported yoke pivotally connected to said feed bar.

10. In a sewing machine of the class described, the combination of supporting means, an upright main driving shaft, stitching mechanism connected therewith, feeding mechanism including a feed device and an upright feed bar connected at one end with said device and at its opposite end with said main driving shaft, a single eccentric connecting mechanism between the upper end of said driving shaft and the upper end of said feed bar, and means for supporting and guiding said feed bar between its ends and comprising a pivotally supported forked yoke pivotally connected to said feed bar.

11. In a sewing machine of the class described, the combination of supporting means having a laterally extending overhanging head, an upright main driving shaft, stitching mechanism connected therewith, and feeding mechanism including a feed device and an upright feed bar connected at one end with said device and at its opposite end with said main driving shaft, and means for supporting and guiding said feed bar between its ends and comprising a double forked yoke pivotally supported by said supporting means and pivotally connected to said bar.

12. In a sewing machine of the class described, the combination of a supporting plate having a laterally extending overhanging head, an upright main driving shaft, stitching mechanism including a needle operating lever pivotally connected with said overhanging head and eccentrically connected with said driving shaft, looper mechanism connected with said nee-

dle lever, and feeding mechanism including a feed device and an upright feed bar connected at its lower end with said feed device and at its opposite upper end having

5 connection with said driving shaft, through the same eccentric connection between the needle lever and shaft.

13. In a sewing machine of the class described, the combination of a supporting plate having a laterally extending overhanging head, an upright main driving shaft, stitching mechanism including a needle operating lever pivotally connected with said overhanging head and connected 10 with said driving shaft, looper mechanism eccentrically connected with said needle lever, feeding mechanism including a feed device and an upright feed bar connected at its lower end with said feed device and 15 at its opposite upper end having connection with said driving shaft to the same eccentric connection between the needle lever and driving shaft, and means pivotally connected with said plate for supporting and guiding said feed bar between 20 its ends and having a pivotal connection with said bar.

14. In a sewing machine, the combination of a main driving shaft, an eccentric thereon 30 adjacent to one end, a feed device in proximity to the opposite end, and means connected with said eccentric and with the feed device for imparting motion to the latter, said feed device having a circular feeding 35 movement including a rising motion thereby tending to lift the loose or free edges of the bag vertically so as to stitch the same across the top uniformly.

15. In a sewing machine, the combination 40 of a main driving shaft, an eccentric thereon adjacent to one end, a feed device in proximity to the opposite end, means connected with said eccentric and with the feed device for imparting motion to the latter, and a 45 pivotally supported bifurcated guide for supporting said means, said feed device having a circular feeding movement including a rising motion thereby tending to lift the loose or free edges of the bag vertically so as to stitch the same across the top uniformly.

16. In a sewing machine, the combination 50 of a main driving shaft, an eccentric thereon adjacent to one end, a feed device, and a feed bar extending from the lower end of the machine to the upper end and connected with said eccentric and with said feed device, said feed device having a circular feeding movement including a rising motion thereby tending to lift the loose or free edges 55 of the bag vertically so as to stitch the same across the top uniformly.

17. In a sewing machine, the combination 60 of a main driving shaft, an eccentric thereon adjacent to one end, a feed device, a feed bar extending from the lower end of the machine

to the upper end and connected with said eccentric and with said feed device, and a pivotally supported yoke for supporting said feed bar between its ends.

18. A sewing machine having feeding 70 mechanism including a feed bar extending from the lower to the upper end of the machine, and means for operating it whereby the feed will have a circular feeding movement including a rising motion thereby tending to lift the loose or free edges of the bag vertically so as to stitch the same across the top uniformly. 75

19. A sewing machine having feeding 80 mechanism including a feed bar extending from the lower to the upper end of the machine, and means including an eccentric connecting means for operating it whereby the feed will have a circular feeding movement including a rising motion thereby tending to 85 lift the loose or free edges of the bag vertically so as to stitch the same across the top uniformly.

20. A sewing machine having feeding 90 mechanism including a feed bar extending from the lower to the upper end of the machine, means including an eccentric connecting means for operating it, and a pivotally supported yoke for supporting said feed bar between its ends. 95

21. In a sewing machine of the class described, the combination of stitching mechanism and feeding mechanism comprising a feed device and a vertically supported bar connected therewith at one end, and means 100 for operating it from its opposite end, thereby to give the feed device a circular movement including a rising motion thereby tending to lift the loose or free edges of the bag vertically so as to stitch the same across 105 the top uniformly.

22. In a sewing machine of the class described, the combination of stitching mechanism and feeding mechanism comprising a feed device and a vertically supported bar 110 connected therewith at one end, and means for operating it from its opposite end and comprising an eccentric and means for driving said eccentric, thereby to give the feed device a circular movement including a rising motion thereby tending to lift the loose or free edges of the bag vertically so as to stitch the same across the top uniformly. 115

23. In a sewing machine of the class described, the combination of stitching mechanism and feeding mechanism comprising a feed device and a vertically supported bar connected therewith at one end, means for operating it from its opposite end and comprising an eccentric and means for driving 120 said eccentric, and a pivotally supported yoke located between the ends of said feed bar. 125

24. In a bag sewing machine, the combination of supporting means having an over- 130

hanging head, a main driving shaft, stitching mechanism including a needle operating lever pivotally connected with said overhanging head and eccentrically connected with said driving shaft at one end, looper mechanism connected with said needle lever, and feeding mechanism including a feed device and a feed bar connected at one end with said feed device and at its opposite end to the same eccentric connection between said needle lever and driving shaft.

25. In a sewing machine of the class described, the combination of a main supporting plate, a bottom plate secured thereto, a laterally extending overhanging arm carried by the supporting plate, and a hinged cover within said arm and coöperating with said main and bottom plates to form a substantially closed casing.

20 26. A bag sewing machine comprising a main supporting plate, a bottom plate secured thereto, a laterally extending overhanging arm carried by the supporting plate, a cover coöperating with said main and bottom plates to form a substantially closed casing, looper and feed mechanisms located within said casing, said feed mechanism including a feed bar extending from one to the opposite end of the machine, and 30 means for operating it comprising a main driving shaft and an eccentric carried thereby, said feed bar being so supported and connected with the driving shaft as to give the feed a circular feeding movement including a rising motion thereby to lift the loose or free edges of the bag vertically so as to stitch the same across the top uniformly.

27. A bag sewing machine comprising a 40 main supporting plate, a bottom plate secured thereto, a laterally extending overhanging arm carried by the supporting plate, a cover coöperating with said main and bottom plates to form a substantially closed casing, looper and feed mechanisms located within said casing, said feed mechanism including a feed bar extending from one to the opposite end of the machine, and a pivotally connected yoke for supporting 45 said bar, said feed bar being so supported and connected with the driving shaft as to give the feed a circular feeding movement including a rising motion thereby to lift the loose or free edges of the bag vertically so as to stitch the same across the top uniformly.

28. A bag sewing machine comprising a main supporting plate, a bottom plate secured thereto, a laterally extending overhanging arm carried by the supporting plate, a cover coöperating with said main and bottom plates to form a substantially closed casing, looper and feed mechanisms located within said casing, said feed mechanism including a feed bar extending from 60 65

one to the opposite end of the machine, a pivotally connected yoke for supporting said bar, and stitch severing means carried by said bottom plate, said feed bar being so supported and connected with the driving shaft as to give the feed a circular feeding movement including a rising motion thereby to lift the loose or free edges of the bag vertically so as to stitch the same across the top uniformly. 75

29. In a bag sewing machine comprising a main supporting plate, a bottom plate secured thereto and having an inclined wall, a presser foot having an inclined end conforming substantially to the angularity of 80 said inclined wall and thereby forming a bag-neck receiving portion, a laterally extending overhanging arm carried by the supporting plate, a cover coöperating with said main and bottom plates to form a substantially closed casing, looper and feed mechanisms located within said casing, said feed mechanism including an upright feed bar extending from one to the opposite end of the machine, a pivotally connected yoke 90 for supporting said bar, means for operating said bar and comprising a main driving shaft and an eccentric connected therewith adjacent to one end and having connection with said feed bar adjacent to its 95 upper end, and stitch-severing means carried by said bottom plate, said feed bar being so supported and connected with the driving shaft as to give the feed a circular feeding movement including a rising motion thereby to lift the loose or free edges of the bag vertically so as to stitch the same across the top uniformly. 100

30. In a sewing machine of the class described, the combination of an upright supporting plate, a bottom plate secured thereto, a laterally extending overhanging arm secured to said upright supporting plate and adapted to carry part of the stitching mechanism at its lower end and a hinged 105 cover plate located within said arm and forming with said bottom and upright plates a substantially closed casing, and mechanism adapted to coöperate with said part of the stitching mechanism and located 110 within said casing. 115

31. In a bag sewing machine comprising an upright supporting plate, a bottom plate secured thereto, a laterally extending overhanging arm secured to said upright supporting plate and adapted to carry part of the stitching mechanism at its lower end and a cover plate forming with said bottom and upright plates a substantially closed casing, and mechanism adapted to 125 coöperate with said part of the stitching mechanism and located within said casing and including a feed bar extending from within the casing to the upper end of the machine and means for operating it, said 130

feed bar being so supported and connected with the driving shaft as to give the feed a circular feeding movement including a rising motion thereby to lift the loose or free edges of the bag vertically so as to stitch the same across the top uniformly.

32. In a bag sewing machine comprising an upright supporting plate, a bottom plate secured thereto, a laterally extending overhanging arm secured to said upright supporting plate and adapted to carry part of the stitching mechanism at its lower end and a cover plate forming with said bottom and upright plates a substantially closed casing, and mechanism located within said casing and including a feed bar extending from within the casing to the upper end of the machine and means for operating it, said operating means being located at the upper end of the machine, said feed bar being so supported and connected with the driving shaft as to give the feed a circular feeding movement including a rising motion thereby to lift the loose or free edges of the bag vertically so as to stitch the same across the top uniformly.

33. In a bag sewing machine comprising an upright supporting plate, a bottom plate secured thereto, a laterally extending overhanging arm secured to said upright supporting plate and adapted to carry part of the stitching mechanism at its lower end and a cover plate forming with said bottom and upright plates a substantially closed casing, mechanism located within said casing and including a feed bar extending from within the casing to the upper end of the machine and means for operating it, said operating means being located at the upper end of the machine, and means connecting that part of the stitching mechanism carried by the laterally extending overhanging arm with the operating means at the upper end of said machine, said feed bar being so supported and connected with the driving shaft as to give the feed a circular feeding movement including a rising motion thereby to lift the loose or free edges of the bag vertically so as to stitch the same across the top uniformly.

34. In a sewing machine of the class described, the combination of a supporting plate having a laterally extending overhanging arm, a needle carried by said arm, a needle lever pivotally connected to said arm, a looper, means connecting the looper with the needle lever, an upright driving shaft, means connecting the needle lever with the driving shaft adjacent to the upper end of the machine, a feed device, an upright feed bar, and means also connecting the upper end of said feed bar with said driving shaft adjacent to the upper end of the machine and through said needle lever connecting means.

35. In a sewing machine of the class described, the combination of supporting means having a laterally extending overhanging arm, needle mechanism carried by said arm and including a pivotally supported needle lever, looper mechanism connected with said needle lever, a main driving shaft, an eccentric carried thereby at the upper end of said machine, a connection between said eccentric and said needle lever, a feed device adjacent to the bottom of said machine, and a feed bar connected with said device and having a connection at its upper end with said eccentric.

36. In a sewing machine of the class described, the combination of supporting means having a laterally extending overhanging arm, needle mechanism carried by said arm and including a pivotally supported needle lever, looper mechanism connected with said needle lever, a main driving shaft, an eccentric carried thereby at the upper end of said machine, a connection between said eccentric and said needle lever, a feed device adjacent to the bottom of said machine, a feed bar connected with said device and having a connection at its upper end with said eccentric, and pivotally supported means having pivotal connection with said feed bar for supporting it between its ends.

37. In a sewing machine of the class described, the combination of supporting means having a laterally extending overhanging arm, needle mechanism carried by said arm and including a pivotally supported needle lever, looper mechanism connected with said needle lever, a main driving shaft, an eccentric carried thereby at the upper end of said machine, a connection between said eccentric and said needle lever, a feed device adjacent to the bottom of said machine, a feed bar connected with said device and having a connection at its upper end with said eccentric, and pivotally supported means having pivotal connection with said feed bar for supporting it between its ends, said pivotally supported means comprising a double bifurcated yoke.

38. In a sewing machine of the class described, the combination of supporting means having a laterally extending overhanging arm, needle mechanism carried by said arm and including a pivotally supported needle lever, looper mechanism connected with said needle lever, a main driving shaft, an eccentric carried thereby at the upper end of said machine, a connection between said eccentric and said needle lever, a feed device adjacent to the bottom of said machine, a feed bar connected with said device and having a connection at its upper end with said eccentric, and pivotally supported means having pivotal connection with said feed bar for supporting it between its ends.

its ends, said pivotally supported means comprising a double bifurcated yoke, and said supporting means having a bottom wall provided with an inclined portion and a 5 presser foot having a similarly inclined portion coöperating with said first inclined portion for guiding the bag necks into position to be stitched.

39. In a sewing machine of the class described, the combination of a supporting member having a laterally extending overhanging arm and a bottom plate, said arm carrying at its lower end a presser foot having an inclined end, and said bottom plate 10 having an inclined wall conforming to the angularity of the inclined portion of said presser foot thereby to form a bag-neck receiving portion.

40. A bag sewing machine comprising a supporting member having a laterally extending overhanging arm and a bottom plate, said arm carrying at its lower end a presser foot having an inclined end and said bottom plate having an inclined wall 20 conforming to the angularity of the inclined portion of said presser foot thereby to form a bag-neck receiving portion, and means carried between said supporting plate and said overhanging arm for stitching and feeding the bag necks.

41. A bag sewing machine comprising a supporting member having a laterally extending overhanging arm and a bottom plate, said arm carrying at its lower end a presser foot having an inclined end and said bottom plate having an inclined wall 30 conforming to the angularity of the inclined portion of said presser foot thereby to form a bag-neck receiving portion, and means carried between said supporting plate and said overhanging arm for stitching and feeding the bag necks.

42. A bag sewing machine comprising a supporting member having a laterally extending overhanging arm and a bottom plate, said arm carrying at its lower end a presser foot having an inclined end and

50 said bottom plate having an inclined wall conforming to the angularity of the inclined portion of said presser foot thereby to form a bag-neck receiving portion, and means carried between said supporting plate and said 55 overhanging arm for stitching and feeding the bag necks, said feeding mechanism including an upright feed bar and means for driving it at its upper end, said means including an upright driving shaft and an eccentric connection between said driving 60 shaft and said feed bar.

43. A bag sewing machine comprising a supporting member having a laterally extending overhanging arm and a bottom 65 plate, said arm carrying at its lower end a

presser foot having an inclined end and said bottom plate having an inclined wall conforming to the angularity of the inclined portion of said presser foot thereby to form a bag-neck receiving portion, means carried 70 between said supporting plate and said overhanging arm for stitching and feeding the bag necks, said feeding mechanism including an upright feed bar and means for driving it at its upper end, said means including an upright driving shaft and an eccentric connection between said driving shaft and said feed bar, and a pivotally supported yoke pivotally connected with said feed bar for guiding and supporting it. 75

44. A bag sewing machine comprising a supporting member having a laterally extending overhanging arm and a bottom plate, said arm carrying at its lower end a presser foot having an inclined end, said 80 bottom plate having an inclined wall conforming to the angularity of the inclined portion of said presser foot thereby to form a bag-neck receiving portion, and stitch-severing means carried by the bottom plate. 85

45. A bag-sewing machine comprising a supporting member having a laterally extending overhanging arm and a bottom plate, said arm carrying at its lower end a presser foot having an inclined end and said 90 bottom plate having an inclined wall conforming to the angularity of the inclined portion of said presser foot thereby to form a bag-neck receiving portion, means carried between said supporting plate and said overhanging arm for stitching and feeding the bag necks, and stitch-severing means carried by said bottom plate. 100

46. In a sewing machine, the combination of a feed device, an upright feed actuating bar, means including a single eccentric for operating said feed bar to impart to the feed device a four motion feed, and means for supporting said feed bar thereby to give to the feed device a circular motion including a rising motion thereby tending to lift the loose or free edges of the bag vertically so as to stitch the same across the top uniformly. 105

47. In a sewing machine, the combination of a feed device, a feed actuating lever extending from the lower to the upper end of the machine, and means including a single eccentric for operating said lever, the organization being such that the feed is given 110 a circular feeding movement including a rising motion and thereby tending to lift the loose and free edges of the bag vertically so as to stitch the same across the top uniformly. 120

48. In a sewing machine, the combination of a feed device, a feed actuating lever extending from the lower to the upper end of the machine, means including a single eccentric for operating said lever, and means 125 130

for supporting said feed bar so that it will rock in transverse planes, the organization being such that the feed is given a circular feeding movement including a rising motion 5 and thereby tending to lift the loose and free edges of the bag vertically so as to stitch the same across the top uniformly.

49. In a sewing machine, the combination of a feed device, a feed actuating bar therefor, means including a single eccentric for 10 operating said feed bar, pivotally supported means for supporting said bar, said pivotally supported means having a pivotal connection with said bar at one end and a 15 guiding connection therewith at its opposite end.

50. In a sewing machine, the combination of a feed device, a feed actuating bar, means for operating said bar, a supporting means

for said bar and comprising a pivotally supported device pivotally supported at one part to said feed bar and having a guiding connection with said bar at another part. 20

51. In a sewing machine, the combination of a feed device, a feed actuating bar, means 25 for operating it, and means for supporting said feed bar and comprising a pivotally supported yoke having one end thereof pivotally connected to said bar and the other end thereof constructed to guide said bar. 30

Signed at Nyack, in the county of Rockland, and State of New York, this 29th day of August, 1914.

JOHN P. WEIS.
